C. C. MURPHY.

CAR ROOF.

APPLICATION FILED MAY 25, 1919.

Patented July 30, 1918.

1,274,308.

UNITED STATES PATENT OFFICE.

CLINTON C. MURPHY, OF CHICAGO, ILLINOIS, ASSIGNOR TO P. H. MURPHY COMPANY, OF PARNASSUS, PENNSYLVANIA, A CORPORATION OF PENNSYLVANIA.

CAR-ROOF.

1,274,308.

Specification of Letters Patent. Patented July 30, 1918.

Application filed May 25 1918. Serial No. 236,491.

To all whom it may concern:

Be it known that I, CLINTON C. MURPHY, a citizen of the United States, and a resident of the city of Chicago, in the county of Cook and State of Illinois, have invented a new and useful Improvement in Car-Roofs, of which the following is a specification.

This invention relates to outside metal car roofs and particularly to that type of car roof wherein the roof sheets are arranged for a limited amount of movement on the roof substructure.

One of the principal objects of the invention is to provide a simple and inexpensive arrangement for securing the roof sheets to the substructure whereby a limited amount of movement of the roof sheets is permitted so that the sheets may accommodate themselves to the weaving and racking motion of the car body while in service. A further object is to eliminate the bossing of the roof sheets, the extra running board saddles and special pivot bearings now commonly used to impart a pivotal movement to the sheets.

The invention consists in a flashing strip adapted to loosely secure the eaves ends of the roof sheets to the car, said flashing strip having portions on which the eaves ends of the sheets rock. The invention further consists in the parts and in the arrangements and combinations of parts hereinafter more fully described and claimed.

In the accompanying drawing, which forms a part of this specification and wherein like numerals refer to like parts wherever they occur,

Figure 1 is a plan view of a portion of a roof embodying my invention, parts being broken away to more clearly illustrate the same;

Fig. 2 is an enlarged vertical section through the eaves portion of the car, the section being taken on the line 2—2 in Fig. 1;

Fig. 3 is a vertical section through the eaves portion of the car on the line 3—3 in Fig. 1;

Fig. 4 is a vertical cross-section through the ridge seam on the line 4—4 in Fig. 1; and

Fig. 5 is a vertical cross-section through the transverse seam on the line 5—5 in Fig. 1.

The roof sheets 6 are loosely arranged on wooden sheathing 7, which may be supported on any suitable substructure. As shown in the drawings, the substructure comprises side plates 8, side sheathing 9 and facia 60 boards 10. The roof sheets are shown extending from eaves to ridge on each side of the car and are provided with upstanding flanges 11 and 12 provided with inturned downwardly inclined extremities at their respective side and ridge margins. Battens 13 extend from eaves to ridge and are nailed or otherwise secured to the roof sheathing between the side flanges of the roof sheets. The side flanges 11 of the sheets on each side 70 of the battens are spaced away from the battens and are loosely connected to each other by inverted channel-shaped transverse seam covers 14. These transverse seam covers have inturned flanges 15, which are hooked 75 under the side flanges 11 of the roof sheets. The ridge ends of the sheets are spaced apart at the ridge and are loosely connected by ridge covers 16 similar to the transverse seam covers 17. These seam covers are provided with inturned flanges 18, which are hooked under the flanges 12 at the ridge end of the sheets. The ridge ends of the transverse seam covers and the ends of the ridge seam covers are secured in position by corner 85 caps 19, which are recessed to receive the seam covers. The eaves ends of the transverse seam covers are held down at the eaves by angle clips 20. The corner caps 19 are secured to the under roof by bolts, which 90 also secure the running board saddles 21 in position. The running boards 22 are secured to the saddles in any suitable manner.

The weight of the running boards and running board saddles is carried by the seam 95 covers and corner caps, thus leaving the sheets free to move under the seam covers. The eaves ends of the roof sheets are turned under and thence downwardly and outwardly as at 23, forming grooves or pockets 100 24 in the under side of the sheets. The eaves ends of the roof sheets are loosely secured to the car substructure by means of a continuous eaves flashing strip, the vertical leg 25 of which is bolted or otherwise secured 105 to the side facia. The eaves flashing strip is provided with an inwardly projecting flange 26, which projects into the pockets 24 of the roof sheets. The flange 26 of the flashing strip is cut at its inner edge into 110

segments of circles forming a scalloped edge portion, which is adapted to bear against the inner wall of the pockets 24 formed on the under side of the roof sheet. The relation between the scalloped edge of the flashing strip and the inner wall of the pocket 24 of the roof sheets is such that the convex or rounded lobe portion 27 formed by scalloping the edge of the flange 26 of the flashing strip is closest to the inner wall of the grooves 24 of the roof sheets at their centers. This arrangement permits the sheets to rock or roll on the lobe portions 27 of the flashing strip, thereby accommodating themselves to the various distortions of the car substructure.

The foregoing described arrangement is considered only as an example and as the one best suited to the type of roof shown. Therefore, I do not wish to be limited to the form of seam shown, as the invention is also applicable to roofs having various forms of flexible seams.

What I claim as my invention is:

25 1. A car roof comprising roof sheets mov-
ably mounted on the substructure, said sheets having grooves formed in their eaves ends, and a strip secured to the eaves of the car and arranged to project into said grooves,
30 the edge portion of the strip which projects into the grooves formed in the roof sheet being spaced from the bottoms of said grooves at different distances.

2. A car roof comprising roof sheets mov-
35 ably mounted on the substructure, said sheets having grooves formed in their eaves ends, and means engaging said grooves for loosely securing the eaves ends of the roof sheets to the car substructure, said means approach-
40 ing the bottom of said grooves more closely at the center of the sheets than at their side margins.

3. A car roof comprising roof sheets ex-
tending from eaves to ridge on each side of the car, said sheets having grooves in the 45 eaves ends and being connected to each other by loose joints at the side and ridge margins, and a continuous angle strip located at the eaves of the car, one of the legs of said angle strip being secured to the side of 50 the car and the other of said legs being ar-
ranged to project into the grooves of a num-
ber of roof sheets, the edge of said last men-
tioned leg of the angle strip being scalloped,
whereby the lobes formed by the scallops 55 are closest to the bottom of the grooves formed in the sheets midway between the side margins of the sheets.

4. A car roof comprising a plurality of roof sheets flexibly connected at the side 60 margins, said sheets having continuous grooves formed in the under sides at the eaves ends, and angle strips secured to the eaves ends of the car, said angle strip hav-
ing inwardly projecting portions extending 65 into the grooves formed in said sheets, the edges of said inwardly projecting portions being scalloped.

5. A car roof comprising roof sheets flexi-
bly secured to each other at their side mar-
gins, the eaves ends of said sheets being re-
bent inwardly and thence outwardly to form 70 grooves in the eaves edges, and an angle strip having one leg secured to the car body,
the other leg of said strip being arranged to 75 project into the grooves in said sheets, the marginal edge of said leg being scalloped and arranged so as to bring the convex por-
tion of the scalloped edge closest to the bot-
tom of the roof sheet grooves midway of the 80 side margins of the sheets.

Signed at Chicago, Illinois, this 20th day
of May, 1918.

CLINTON C. MURPHY.
